(57) CLAIM

The ornamental design for a towel dispenser, as shown and described.

DESCRIPTION

FIG. 1 is a front right-side perspective view of a towel dispenser, shown in use with a paper towel;

FIG. 2 is a front view of the towel dispenser;

FIG. 3 is a rear view thereof;

FIG. 4 is a right-side view thereof;

FIG. 5 is a left-side view thereof;

FIG. 6 is a right-side view of the towel dispenser, shown with the right-side cap removed for ease of disclosure;

FIG. 7 is a top view of the towel dispenser;

FIG. 8 is a bottom view thereof;

FIG. 9 is a top front right-side perspective view of the towel dispenser, shown in an open state of use;

FIG. 10 is another perspective view thereof; and,

FIG. 11 is a bottom front left-side perspective view thereof. The broken line showing of portions of the towel dispenser and the paper towel roll depict unclaimed portions and form no part of the claimed design.

1 Claim, 11 Drawing Sheets
